UNITED STATES PATENT OFFICE.

CHESTER B. LIEBCHER, OF LONG BEACH, CALIFORNIA.

CLOTHES-WRINGER.

1,108,589.

Specification of Letters Patent. Patented Aug. 25, 1914.

Application filed June 2, 1914. Serial No. 842,419.

To all whom it may concern:

Be it known that I, CHESTER B. LIEBCHER, a citizen of the United States, residing at Long Beach, in the county of Los Angeles 5 and State of California, have invented certain new and useful Improvements in Clothes-Wringers, of which the following is a specification.

My invention relates to improvements in 10 clothes wringers having adjustable yielding means for moving the rolls included therein toward each other.

An important object of the invention is to provide apparatus of the above mentioned 15 character, which is simple in construction, inexpensive to manufacture, formed of few and simple parts which are arranged in a compact manner, and convenient in use.

Other objects and advantages of the invention will be apparent during the course 20 of the following description.

In the accompanying drawings forming a part of this specification and in which like numerals are employed to designate like 25 parts throughout the same, Figure 1 is a side elevation of apparatus embodying my invention, Fig. 2 is an edge elevation of the same, Fig. 3 is a longitudinal sectional view taken on line 3—3 of Fig. 1, Fig. 4 is a fragmentary edge elevation of the frame, with certain elements removed for the sake of clearness, and Fig. 5 is a horizontal sectional view taken on line 5—5 of Fig. 2.

In the drawings, wherein for the purpose 35 of illustration is shown a preferred embodiment of the invention, the numeral 10 designates vertical standards of a frame, rigidly connected near their lower ends by a transverse strip 11. The standards 10 are provided in their upper portions with longitudinally extending openings 11', provided upon their side walls with grooves 12', as shown in Fig. 5. The upper ends of the standards 10 are rigidly connected by a horizontal transverse bar 12 extending into the 40 upper ends of the longitudinal openings 11'. Transverse bolts 13 pass through the upper ends of the standards 10 and through the ends of the bar 12, and also through inverted U-shaped brackets 14. Longitudinally 45 movably mounted within the openings 11' are upper and lower bearing blocks 15 and 16. Each of these bearing blocks, as more clearly shown in Fig. 5, are provided

with longitudinal ribs 17, to operate within 55 the grooves 12'.

The upper bearing blocks 15 have a rotatable operating shaft 18 journaled therethrough, the same being held against longitudinal movement by rings 19 rigidly 60 mounted thereon. The shaft 18 is turned by a hand wheel 18'. This rotatable shaft 18 is provided with right and left hand screw-threads, receiving longitudinally movable blocks or members 20, having right and left 65 hand screw-threaded openings, as is obvious. The blocks 20 are prevented from turning upon their longitudinal axes by a guide-rod 21, the ends of which pass through apertures in the lower ends of the upper bearing 70 blocks 15. These bearing blocks may be vertically moved or adjusted by bolts 22, having screw-threaded engagement with the ends of the bar 12 with their lower ends swiveled to the upper end of the blocks 15, 75 by any well known or preferred means. These adjusting bolts 22 have heads 23, provided with transverse apertures to receive a tool (not shown), for turning them.

Vertically movably mounted within the 80 openings 11' is a presser bar or member 24, which is straddled by U-shaped brackets or members 25, the same being pivoted thereto by bolts 26. The U-shaped brackets 25 are provided with axially extending openings 85 27, to receive longitudinally movable bars 28, the lower ends of these bars being provided with elongated slots 27', to receive bolts 26. The upper ends of the bars 28 are provided with U-shaped heads 29, which are 90 forked to straddle the blocks 20 and are pivoted thereto by means of transverse bolts 30. Surrounding the bars 28 are suitably stiff compressible coil springs 31, which engage the heads or brackets 25 and 29, as 95 shown. It is thus seen that longitudinally extensible members are provided to connect the blocks 20 and presser bar or member 24, the same having yielding or spring means to retain them distended.

Suitably journaled through the lower portions of the vertically adjustable bearings 16 is a transverse rotatable shaft 32, upon which is rigidly mounted an upper roll 33. The bearings 16 extend upwardly above the 105 roll 33 for a substantial distance, to be engaged by the depressing member 24. The depressing member 24 is shown in its ele-

vated position out of engagement with the bearings 16.

The numeral 34 designates a lower transverse rotatable shaft, upon which is rigidly mounted a lower roll 35, adapted to co-operate with the upper roll 33. The shaft 34 is suitably journaled through standards 10 or through bearings carried thereby. Rigidly mounted upon the outer ends of the shafts 32 and 34 are gear wheels or pinions 35' and 36, engaging each other to positively connect the rolls. These gear wheels are preferably of the type shown, each comprising a double set of gear teeth. The lower shaft 34 is rotated by means of a crank 37 or the like.

In the operation of the apparatus, the upper roll 33 will be moved toward or away from the lower roll 35 to increase or decrease pressure that the same will exert upon the clothes passing therebetween by rotating the hand wheel 18. The springs 31 serve to yieldingly hold the upper roll in place, but allowing the same to move upwardly in case of an obstruction passing between the rolls, such as a button. The rolls are rotated by the crank 37, such rolls being pivotally geared together.

It is to be understood that the form of my invention herewith shown and described is to be taken as a preferred example of the same, and that various changes in the shape, size, and arrangement of parts may be re-

sorted to without departing from the spirit of the invention or the scope of the subjoined claim.

Having thus described the invention, I claim:

In a clothes wringer of the character described, a frame, an operating shaft connected therewith and provided with right and left screw-threads, means to rotate the operating shaft, blocks having screw-threaded openings to receive the screw-threaded portions of the operating shaft, a movable depressing member, longitudinally extensible members pivotally connected with the blocks and with the depressing member, means to prevent the blocks from turning upon their longitudinal axes, coil springs surrounding the longitudinally extensible members to normally maintain the same extended, vertically movable bearings slidably engaging the frame and adapted to be engaged by the depressing member, an upper roll carried by the bearings, a lower roll arranged within the frame to co-operate with the upper roll, and means to drive the shaft.

In testimony whereof I affix my signature in presence of two witnesses.

CHESTER B. LEBCHER.
